UNITED STATES PATENT OFFICE.

JOHN WRIGHT, OF HOOSICK FALLS, NEW YORK.

WHISK-BROOM HOLDER.

SPECIFICATION forming part of Letters Patent No. 372,835, dated November 8, 1887.

Application filed December 13, 1886. Serial No. 221,395. (No model.)

To all whom it may concern:

Be it known that I, JOHN WRIGHT, a citizen of the United States, residing at Hoosick Falls, in the county of Rensselaer, State of New York, have invented certain new and useful Improvements in Whisk-Broom Supports, of which the following is a specification, reference being had therein to the accompanying drawings.

10 This invention relates to whisk-broom supports; and my object is to provide an ornamental bracket or support for the broom, which is adapted to be secured to a wall to form a ready and accessible means for receiving, holding, and allowing the broom to be withdrawn therefrom, and this, preferably, without the visible presence of screws or other fastening or securing devices.

With these objects in view the invention 20 consists in certain features of construction, hereinafter described, and particularly pointed out in the claim.

Referring to the drawings, Figure 1 represents a perspective of my invention, a whisk-broom mounted therein. Fig. 2 is a rear view. Fig. 3 is a vertical section of the base taken on the line *x x* of Fig. 1. Fig. 4 is a similar view taken on the line *y y* of Fig. 1, and Fig. 30 is a central vertical section, showing the 30 means employed for securing the bracket or base to the wall.

Similar letters of reference indicate like parts in all the figures of the drawings.

A represents a bracket or base, in this instance of wood and of shield form, but which, if desired, may be of other suitable material and of any desired form. In the back of the base A is a recess, *a*, in which is secured, by screws *a'*, a plate, *b*, having an inverted key-hole slot, *c*. This plate may be either set in the back of the base and flush with its outer surface, as shown in Fig. 5, or simply secured thereupon, as shown in Fig. 2. To the front of the base, and at a suitable point thereon, is secured a broom-embracing arm or horn, B, which naturally projects out from and across the bracket or base, forming a receptacle for the broom. In this instance I have made the embracing horn or arm in the shape of a horn, 50 and prefer employing a real or natural horn

for this purpose, as shown in the drawings. Secured within the base of the horn is a wooden plug, *b*, into which a screw, *b'*, passes from the back of the base. Small tacks or pins, as *b''*, may be employed to ornament or further aid 55 or act solely to secure the horn or arm rigidly to the base, if desired. At one side of the base or bracket—in this instance near its upper corner—is secured a match or toothpick safe or receptacle, D, which in this instance I form 60 by sawing off a portion of the base of the horn employed for the broom. After being separated from the horn by simply splitting it longitudinally and mounting it in a base, as *d*, secured to the bracket, an ornamental receptacle is provided.

By reason of the smooth surface of the horn, I prefer it, or material resembling the same, for the purpose described, in that it permits of an easy insertion and withdrawal of the 70 broom, besides giving the article a very finished and highly-ornamental appearance.

Either one or two screws or other retaining devices, as *g*, may be employed to retain the bracket upon the wall, the operation of securing the bracket in position being merely to insert the screw or screws in proper alignment and relative position with each other, and then inserting the heads thereof through the enlarged portion of the slot *c* and lowering 80 the bracket, so that the screws or nails will be in the position shown in Fig. 5.

If desired, a screw or other retaining device may be inserted through the back of the bracket into the tip of the horn, as shown at *f*. 85

The susceptibility of natural horns to a high polish gives to my broom-holder a unique and finished appearance, while the natural curvature of horns is such that it can be, without further treatment, utilized for the purpose 90 specified. Still I do not limit my invention to the employment of natural horn or horns, as artificial horns may be made of celluloid, wood-paper pulp properly finished, or any other desired material, as heretofore stated.

The object of employing two screws, as *g*, is to prevent sidewise swinging of the holder when suspended, the upper screw of the pair being first inserted into the eye of the key-hole slot and the holder lowered until the sec- 100

ond or lower screw is reached, when that also is entered, and both are retained within the elongation of the slot.

Having described my invention, what I

5 claim is—

The base A, provided with the broom-supporting arm B, having the plug or core b mounted therein and secured at one side of

the base by means of the screw b', substantially as specified.

In testimony whereof I affix my signature in presence of two witnesses.

JOHN WRIGHT.
